UNITED STATES PATENT OFFICE.

ANNIE M. GROSS, OF PHILADELPHIA, PENNSYLVANIA.

CURTAIN-HOLDER.

1,345,170.

Specification of Letters Patent. Patented June 29, 1920.

Application filed November 8, 1918. Serial No. 261,676.

To all whom it may concern:

Be it known that I, ANNIE M. GROSS, a citizen of the United States, resident of Philadelphia, in the county of Philadelphia and State of Pennsylvania, have made a certain new and useful Invention in Curtain-Holders; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention, as applied.

Fig. 2 is a similar view, with the parts in position to receive the curtain, in placing the same in position.

Fig. 3 is a fragmentary perspective view showing a double device.

Fig. 4 is a central horizontal longitudinal section of the holder with parts broken away.

The invention has relation to curtain holders having for its object to provide an improved holder having means adapted to facilitate the placing thereon of the curtain and the removal of the same.

The invention consists in the novel construction and combinations of parts as hereinafter set forth.

In the accompanying drawings illustrating the invention, the numeral 2 designates end bracket plates secured to the window casing 3, and each bearing a tubular carrier member or rod 4, pivoted to the bracket at 5, and extending outwardly and then laterally through a curved bend 6, the two rods projecting toward each other in alignment and being spaced apart. A rod 7 of suitable length slidably engages at both ends with the outer terminal portions of the bores of and connects the carrier rods. Preferably a second rod 8 of greater diameter than and surrounding the inner rod slidably engages at its ends over the outer terminal portions of and connects the carrier rods, both rods 7 and 8 being of substantially the same length. When both connecting rods are used, the inner rod need be engaged with but one of the carrier rods.

In use, the outer connecting rod 8 is slid endwise in one direction to disengage it at one end from one of the carrier rods, being then slid endwise in the opposite direction

but not sufficiently to clear the inner rod 7, upon which one end of the outer rod rests and is supported to form an extension rod made up of both rods 7 and 8, and of the 60 lateral extension of the carrier rod, as shown in Fig. 2 of the drawings. The inner rod 7 may be regarded as an extension or part of the carrier rod at either side. In the operation stated and prior to the second or last 65 named movement of the connecting rod, both rods 7 and 8 and the carrier rod are swung in a vertical plane upon the carrier rod pivot as a center to bring the two carrier rods out of alinement and enable the extension to be made.

The curtain is now slipped over the connecting rod as shown, and curtain and rod together slid endwise until the rod is re-engaged with the carrier rod and again entirely surrounds the inner rod 7. Both rods 7 and 8 and the carrier rod are then turned pivotally to a slight degree upon the carrier rod pivot as a center to bring the carrier rods and the rods 7 and 8 into alinement 80 again and the outer connecting rod slid endwise to reengage it with the other carrier rod.

The connecting rod may be disengaged with either of the carrier rods preliminary 85 to placing the curtain in position, thereby enabling the extension of the rods to be made toward and the curtain to be slipped on from either side of the window, and owing to the extension of the connecting rod 90 upon the inner rod to an extent which may vary as desired, the curtain is enabled to be more conveniently placed in position, the inner rod from its support in the carrier rod bearing the weight of the outer rod and of 95 the curtain. And owing to the outer or connecting rod upon which the curtain is placed being of greater diameter than the carrier rods, the curtain may be spread laterally to its full width without obstruction. 100

This curtain holder is made in different sizes to accord with the size of the window to which it is to be fitted, and in placing the curtain in position thereon and in removing the same, the holder rods are not detached from the holder. The holder may be made single, double or triple, and in Fig. 3 a double holder is shown.

I claim:

In a curtain holder, end bracket plates 110 adapted to be secured to the window casing and spaced apart, tubular angular carrier

members also spaced apart and having pivotal connection with said bracket plates to swing in a vertical plane and extending toward each other, a straight inner rod of a 5 diameter to fit neatly within the bore of and bridging said members and slidably adjustable to escape from one of said members and engage the other member alone, and an outer straight tubular curtain-carrying rod 10 of a diameter to fit neatly over and also bridging said members and slidably adjustable to escape from one of said members and engage the other member alone, both of

said rods being slidable in one direction to escape from one of said carrier members 15 and adjustable in a vertical plane upon pivotal movement of the other carrier member, and said outer rod being slidable upon said inner rod as a guide in placing the curtain upon the holder. 20

In testimony whereof I affix my signature in presence of two witnesses.

A. M. GROSS.
